(57) **CLAIM**

The ornamental design for a guiding catheter tip, as shown and described.

DESCRIPTION

FIG. 1 is a perspective view of an ornamental design for a guiding catheter tip in accordance with the present invention; FIG. 2 is a first side elevational view thereof; FIG. 3 is a second side elevational view thereof;

FIG. 4 is a top elevational view thereof;

FIG. 5 is a bottom elevational view thereof;

FIG. 6 is a first end elevational view thereof; and,

FIG. 7 is a second end elevational view thereof.

The broken lines shown in the figures are included for the purpose of illustrating portions of the article and form no part of the claimed design.
